BUILDING BLOCK

Victor A. Rigamont, Pittsburgh, Pa.

Application January 6, 1944, Serial No. 517,155

2 Claims. (Cl. 72—38)

1

This invention relates to building members and, in particular to a brick or block suited for the construction of walls.

Masonry walls as constructed of conventional brick are characterized by serious objections. The spacing between successive courses of bricks and the spacing between the individual bricks of a course are wholly dependent upon the skill and judgment of the bricklayer. The mortar bond, furthermore, is the only thing which provides resistance to lateral thrust. Unless conventional bricks are laid with extreme care, a wall composed thereof is likely to permit seepage of rain water therethrough with resulting dampness on the interior of a building. The provision of raked joints on the exterior of a wall for the sake of improving appearance consumes much of the mason's time and is accordingly quite costly.

I have invented a novel form of building brick or block which overcomes the aforementioned objections to conventional brick and also has the advantage of using less mortar than ordinary bricks when laid in a wall. In a preferred embodiment, my brick comprises a body portion having substantially the shape of a right rectangular prism with integral spacer ribs extending along the top face and one end face, the ribs being adjacent the side faces of the body portion but spaced slightly inwardly therefrom. My brick also has a raised portion extending along the bottom and upwardly across one end face. This brick is suited for use as a stretcher. I also provide bricks having the same novel features but with suitable modifications for use as headers and at inside and outside corners.

Further details, novel features and advantages of the invention will become apparent during the following complete description thereof which refers to the accompanying drawings illustrating a few forms of the brick of my invention.

In the drawings,

Figure 1 is a plan view of my stretcher brick;

Figure 2 is an end view looking from the left in Figure 1;

Figure 3 is an end view looking from the right in Figure 1;

Figure 4 is a side elevation;

Figure 5 is a bottom plan view;

Figure 6 is a partial section through adjacent courses one brick deep, laid up with brick of my invention;

Figure 7 is a plan view of a brick for use at an outside corner in a stretcher course;

Figure 8 is a side elevation thereof;

2

Figure 9 is a rear elevation thereof;

Figure 10 is a plan view of a brick suited for use at an inside corner of a header course;

Figure 11 is a side elevation thereof;

Figure 12 is a rear elevation thereof;

Figure 13 is a plan view of a header brick embodying my invention;

Figure 14 is a side elevation thereof;

Figure 15 is a rear elevation thereof;

Figure 16 is a partial plan view of a stretcher course showing inside and outside corners;

Figure 17 is a similar view of a header course, and

Figure 18 is a partial elevation of a corner of a wall composed of brick of my invention.

Referring in detail to the drawings and, for the present, to Figures 1 through 5, my stretcher brick 10 comprises a body portion 11 having a shape of a right rectangular prism. In fact, the body portion 11 may be similar in size and shape to conventional brick. Spacer ribs 12 and 13 extend along the top face of the body portion adjacent the side faces thereof but shaped inwardly therefrom. The ribs 12 and 13 are preferably formed

integral with the body portion. The ribs 12 and 13 continue downwardly across one end face of the body portion as indicated at 14 and 15. The height of the ribs is preferably about equal to the thickness of mortar used in laying conventional bricks.

A raised portion or key 16 extends centrally along the bottom face of the body portion and continues upwardly as at 17 across the end face thereof opposite that on which the ribs 14 and 15 are formed. The raised portion is also

preferably formed integral with the body portion. It will be apparent that the brick 10 may be made by the conventional extrusion method with special provisions for cutting the ends to the desired shape, as shown in Figures 1 and 5.

Figure 6 illustrates a portion of a wall laid up with bricks of my invention. As clearly shown, the ribs 12 and 13 serve to separate the body portions of brick of adjacent courses from each other by a predetermined spacing which is the same in all cases. The positioning of the ribs 12 and 13 inwardly from the side faces of the body portion gives the appearance of raked joints in the finished wall. In laying the bricks of my invention, the ribs 12 and 13 are disposed uppermost, as shown in Figure 6, and mortar is placed between them, as shown at 18. When bricks are laid on a preceding course the raised portion 16 penetrates the mortar and, when the latter has set, effectively keys adjacent courses, thereby providing substantial resistance to lateral thrust.

A considerable saving in mortar is effected by reason of the fact that the raised portion 16 depends into the mortar space between the ribs 12 and 13. It will be understood that the mason will judge the amount of mortar required, making sure to err on the side of too little rather than too much, since it is not essential that the mortar space be entirely filled. As a matter of fact, even if too much mortar is applied, the brick may be so laid that the excess will be squeezed out at one end and will not interfere with the proper seating of the brick of one course on the ribs of the bricks of the preceding course. This may be done by pressing the end of the brick being laid, down on the ribs of the preceding course at the end adjacent the last brick laid, and then pressing down the other end of the brick. This eliminates the loss of mortar which occurs in the laying of a wall with conventional bricks when the mason "strikes" the joints to cut off excess mortar squeezed out at the side as the bricks are pressed down in the mortar. Since the bricks are not mortared to the extreme edges, and the ribs confine the mortar applied, there is no sloping of mortar down the sides of the wall, thus effecting a further saving in the amount of mortar used.

It will be apparent that the joint 19 between the ribs of one course and the bottom of the bricks of the next course above is protected from the weather by the overhang of the brick thereabove. By reason of this fact, rain striking the outside of a wall composed of my bricks is shed effectively. The rain water running down the face of a brick falls off of the overhanging lower edge, instead of tending to flow through the joint. This practically eliminates seepage and makes the wall thoroughly weather tight since leakage of cold air is prevented in the same manner as the seepage of rain water. At the end joints between bricks, a similar water and air stop results from the cooperation of the raised portion 17 at the end of one brick with the ribs 14 and 15 at the end of the abutting brick, as clearly shown in Figure 16, which will be referred to in due course. Even if rain water should seep through the joint on the outer side of the wall, it is effectively stopped by the rib on the inner side, since the latter constitutes a continuous barrier.

Figures 7, 8 and 9 show a special form of brick 20 for use in stretcher courses at the outside corner of a wall, such as that illustrated at 21 in Figure 16. The brick 20 has ribs 22 and 23 like the ribs 12 and 13 of brick 10. A rib 24 forms a continuation of rib 22 across one end of the brick. The rib 23 terminates short of that end of the brick. Ribs 25 and 26 extend downwardly across a side face of the brick from the ends of ribs 23 and 24. The brick 20 also has a raised portion or key 27 disposed centrally of the bottom thereof and a corresponding portion 28 extending upwardly from the bottom across the other end of the brick. As clearly shown in Figure 16, the bricks 20 at the outside corner 21 of the wall cooperate with the bricks in courses at right angles to each other. That is to say, the left-hand end of the brick 20, as shown in Figures 7 and 8, engages the ribbed end of the stretcher brick 10 in the same manner as the abutting ends of all adjacent bricks. At the same time, the side of the brick 20 having the ribs 25 and 26 has the same relation to the adjacent end of an abutting brick. The rib 24, furthermore, provides a continuous water stop across the end

of the brick and leaves the wall corner fully finished.

Bricks 20a generally similar to but differing slightly from bricks 20 are laid at the inside corner 21a of stretcher courses.

It will be understood that while the corner 21 has been referred to as an outside corner and the corner 21a as an inside corner, it is immaterial which one is considered the outside or the inside since either face of the wall of Figure 16 could be considered the interior.

Figures 10, 11 and 12 show a brick 29 adapted to be laid in header courses at an inside wall corner such as shown at 30 in Figure 17. The brick 29 has ribs 31 and 32 corresponding to the ribs 12 and 13 of brick 10. A rib 33 continues from one end of rib 31 across the width of the brick. The rib 32 terminates short of that end of the brick. Ribs 34 and 35 extend downwardly from the ribs 31 and 32 across the other end of the block. A centrally disposed raised portion or key 36 is formed on the bottom of the brick and a similar portion 37 on one side between the ribs 32 and 33. The bricks 29, as shown in Figure 17, have the same engagement with adjacent header bricks 38 in courses at right angles as is provided between adjacent header bricks laid side by side, in the portions of the wall between corners.

Figures 13, 14 and 15 illustrate the header or bonder brick 38 for use in the header courses which are laid at intervals in the building up of a wall. The header brick has spacer ribs 39 and 40 extending across the top adjacent each end but spaced slightly inwardly thereof. Spacer ribs 41 and 42 continue downwardly across one side face from the ribs 39 and 40. Spaced raised portions or keys 43 and 44 extend across the bottom face of the brick and similar raised portions 45 and 46 extend upwardly from the bottom across the side face opposite that on which the ribs 41 and 42 are formed.

Figure 17 shows how the header bricks 38 engage each other when laid up in a course. It will be evident that the ribs 39 and 40 serve as spacers and water stops in the same manner as the ribs 12 and 13 of the stretcher bricks 10. Figure 17 also shows bricks 47 for use in header courses at outside corners such as 48. These bricks are not identical with the bricks 20 and 29 but are generally similar thereto and the details of the former will be apparent from the above description of the latter, taken together with the showing of Figure 17. Figure 17 also illustrates half bricks 49 which are needed to fill out the header course adjacent the corners. These half bricks are similar to the bricks 10 but are only half the length thereof.

Figure 18 illustrates the appearance of a corner in a wall composed of bricks according to my invention. As is shown, the wall has the appearance of an ordinary brick wall with raked joints. The spacing between bricks is uniform, however, since the body portion of each brick is seated firmly on the ribs on top of the brick in the course below. The joints between the ribs of one brick and the body portion of adjacent bricks thus appear merely as fine lines and are particularly invisible.

It will be apparent from the foregoing description that my invention is characterized by numerous advantages over conventional bricks. In the first place, the spacing between adjacent bricks is uniform at all points, as explained above. The interfitting ribs and raised portions of adjacent

bricks further provide a mechanical interlock which imparts great strength to the wall in resistance to lateral thrust. The spacing of the ribs inwardly from the side faces of the bricks gives the finished wall the appearance of having been laid with raked joints. This is one of the more costly finishes when used in a wall composed of conventional brick but does not introduce any additional expense in a wall constructed of bricks of my invention. The function of the ribs in providing a stop against the entry of wind and water has already been sufficiently explained as has also the matter of saving in mortar effected by my invention as compared with conventional construction of masonry walls.

Although I have disclosed but a few forms of bricks embodying the principle of my invention, it will be apparent that other forms may be provided utilizing similar principles, for various special functions. Such modifications of the general idea may, of course, be made without departing from the spirit of the invention or the scope of the appended claims.

1. A building block comprising a body having two opposite ends and four lateral sides defining a right rectangular prism, a pair of spaced ribs projecting integrally from two contiguous lateral sides of said body, and a plurality of spaced keys projecting integrally from the other two lateral sides of said body, said ribs and keys all extending parallel to said opposite ends of the body, one rib being adjacent one of said ends and the other rib being adjacent the other of said ends, and said keys being spaced substantially further inwardly of said ends than said ribs, and the projection of said ribs from said body being greater than the projection of said keys from said body, whereby a series of such blocks in a wall are in contact with each other only where the ribs of the respective blocks are in contact with the lateral sides of adjacent blocks, the keys of each block being entirely out of contact with any portion of the adjacent blocks.

2. A building header block comprising a body having two opposite ends and four lateral sides defining a right rectangular prism, a pair of

spaced ribs of equal and substantially square cross-section projecting integrally from two contiguous lateral sides of said body, and a pair of spaced keys of equal and substantially rectangular cross-section projecting integrally from the other two lateral sides of said body, said ribs and keys all extending parallel to said opposite ends of the body, one rib being adjacent one of said ends and the other rib being adjacent the other of said ends, and said keys being spaced substantially further inwardly of said ends than said ribs, and the projection of said ribs from said body being about twice the projection of said keys from said body, whereby a series of such blocks in a wall are in contact with each other only where the ribs of the respective blocks are in contact with the lateral sides of adjacent blocks, the keys of each block being entirely out of contact with any portion of the adjacent blocks.

Certificate of Correction

Patent No. 2,482,719

September 20, 1949

VICTOR A. RIGAUMONT

It is hereby certified that errors appear in the printed specification of the above numbered patent requiring correction as follows:

Column 2, line 23, for "shaped" read *spaced*; column 4, lines 68 and 69, for "particularly" read *practically*;
and that the said Letters Patent should be read with these corrections therein that the same may conform to the record of the case in the Patent Office.

Signed and sealed this 17th day of January, A. D. 1950.
